UNITED STATES PATENT OFFICE.

WILLIAM BROWN COGGER AND HENRY A. HAMLIN, OF MINNEAPOLIS, MINN.

DOOR-HANGER.

SPECIFICATION forming part of Letters Patent No. 283,208, dated August 14, 1883.

Application filed October 13, 1882. (Model.)

To all whom it may concern:

Be it known that we, WILLIAM B. COGGER and HENRY A. HAMLIN, of Minneapolis, in the county of Hennepin, and in the State of Minnesota, have invented certain new and useful Improvements in Door-Hangers; and we do hereby declare that the following is a full, clear, and exact description thereof, reference being had to the accompanying drawings, and to the letters of reference marked thereon, making a part of this specification.

This invention relates to certain improvements in hanging and sliding doors; and it has for its object to obviate the objections which have heretofore existed in regard to this class of doors, such doors requiring skilled labor in hanging, and are liable to become disarranged by the settling of the structure or the springing of the studs from which the doors are suspended; and it consists in the devices herein-after described, and pointed out in the claims.

In the accompanying drawings, forming a part of this specification, and in which like letters of reference indicate corresponding parts, Figure 1 represents a view partly in section and partly in elevation of our invention, and Fig. 2 represents a vertical transverse section on the line $x-x$ of Fig. 1.

In the drawings, the letter A indicates two brackets, each of which consists of a head or cross-piece, A', and two vertical extensions, a, the lower extremities of the latter terminating in lateral projections or seats C. These brackets are made of cast metal, preferably iron, and at suitable points are provided with screw or other fastening apertures, by which they are secured to the studs of the building. To the lower ends of these brackets are attached, by any suitable means, the rails B, the said rails in the present instance being located in seats C, as shown in Fig. 2. Upon the said rails are arranged to travel the flanged wheels D, the axles E of which set between the lugs F of the plates G, which rest upon said axle and play loosely thereon as the door is moved back and forth. The said plates are attached to the under side of the bar H by means of screws or otherwise. Through the said bar and the plates at the ends extend the hangers I, which are screw-threaded at their upper ends and supported by screw-nuts K.

These hangers extend down between the respective wheels at the ends of the bar, and are bent toward each other at the lower ends, forming studs, having buttons L at their extremities. 55

The letter M indicates the door, and N the stiles thereof, which are provided with recesses P, for the purposes hereinafter explained. Through the stiles extend vertically from the recesses the rods R, which are flattened at their upper ends, and provided with slots S, terminating below in apertures T, the apertures being of such size as to pass readily over the buttons at the ends of the hangers, 65 and the slots of such width as to embrace the shanks of the buttons, so as to securely hold the rods and suspend the door.

The above-mentioned bar H is in length equal to the width of the door, and two pairs of rollers are provided for the bar. By means of the nuts U, which set into the recesses P and are secured to the screw-threaded lower ends of the rods R, the door may be adjusted to compensate for sagging. 70

The brackets, which may be made of metal or wood, are fastened to the studding of one of the partitions, forming the space in which the door travels. After the said brackets are properly adjusted, the other partition may be 80 set in place without regard to the tracks, as the brackets before mentioned hold them in place. 75

The under edges of the brackets, it will be observed, are curved to allow the passage of the 85 wheels and bar and prevent the tracks from spreading or closing, which would interfere with the proper operation of the wheels.

Having thus described our invention, what we claim as our invention, and desire to secure 90 by Letters Patent, is—

1. In a door-hanger, the combination, with the cast-iron brackets A, consisting each of the respective heads or cross-pieces A', and the vertical extensions a, having each apertures 95 for the fastening-screws, and terminating in lugs, forming track-rail seats, of the track-rails B, fitted to and supported by the said lugs, the respective brackets being each located at or near the ends of the tracks, as and for the purpose shown and described. 100

2. The combination, with the roller-bar H,

of the hangers I, provided with lateral lower extremities having suitable buttons, L, and the rods R, slotted and provided with apertures, as described, the said rods being secured 5 to the stiles of the door and adapted to connect with the hangers to support the door, substantially as specified.

In testimony whereof we affix our signatures,

in presence of two witnesses, this 7th day of September, 1882.

WILLIAM BROWN COGGER.
HENRY A. HAMLIN.
